(57) **CLAIM**

The ornamental design of a light emitting diode, as shown and described.

DESCRIPTION

FIG. 1 is a top, front, right isometric view of portions of a light emitting diode showing our new design;

FIG. 2 is a bottom, front, left isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left elevation view thereof; and,

FIG. 8 is a right elevation view thereof.

Features of the drawing figures shown in dashed lines are for illustrative purposes only and form no part of the claimed design of the subject embodiment.
